UNITED STATES PATENT OFFICE.

OSCAR C. STAPLES, OF TULSA, OKLAHOMA.

SAFETY C LINK.

Application filed October 13, 1924. Serial No. 743,378.

To all whom it may concern:

Be it known that OSCAR C. STAPLES, citizen of the United States of America, residing at Tulsa, in the county of Tulsa and State of Oklahoma, have invented certain new and useful Improvements in Safety C Links, of which the following is a specification.

This invention relates to new and useful improvements in safety C-links.

It is customary to pump several oil wells with one engine driving a pumping power from which two or more pump jacks at the wells, are operated by connecting rods.

Each connecting rod includes a C link located between the pump jack and the pumping power and which may be disconnected to separate the connecting rod when it is desired to stop pumping a particular well. As no provision is made in the links now in common for protecting the fingers and knuckles of the operator and as he must insert his hand in the link to grasp it, injury frequently results.

The object of my invention is primarily to provide a safety link having a hand grip which may be grasped by the operator without exposing any part of his hand to the rod connections which move inside of the link.

Another important object is to reinforce the link and thus preclude breakage and distortion which is quite common with the links now in common use.

A further object is to provide a link with a latch to prevent it from being detached unintentionally.

A construction designed to carry out the invention will be hereinafter described together with other features of the invention.

The invention will be more readily understood from a reading of the following specification and by reference to the accompanying drawings, in which an example of the invention is shown, and wherein:

Fig. 1 is a view in elevation showing a link constructed in accordance with my invention connected in a pumping rod.

Fig. 2 is an enlarged cross-sectional view on the line 2-2 of Fig. 1,

Fig. 3 is an elevation of a link constructed in accordance with my invention and including a latch, and

Fig. 4 is a cross-sectional view on the line 4-4 of Fig. 3.

In the drawings the numeral 10 designates a C link having the usual shape. Along the closed side of the link is formed a radial web 11 which is merged from the body of the link and gradually reduces in thickness to its outer edge. In this web is provided a longitudinal opening 12 parallel to the body of the link and the outer edge of the web. This opening is of such length and width as to freely admit the fingers and knuckles of the hand of the operator. That narrow portion 13 of the web lying outwardly of the opening and contiguous thereto constitutes a hand grip by which the link may be grasped and held.

The web reinforces and strengthens the link. At each end of the form shown in Figs. 1 and 2 is a fin 14 which is merged out of the web, as a continuation and curved around the ends of the link, its radius gradually decreasing until it vanishes into the hook 15 of the link. It will be seen that the plane of the fin is parallel to the pull of the rod and defeats the tendency of the hook of the link to spread or elongate under an excessive load.

In Figs. 3 and 4 I have shown another form in which the fin 14' at one end is shortened and merged into a rounded boss 16, the latter having an axial bore 17 which is continued through the bill of the hook to a shoulder 18 at the inner end of a counter bore 19. The head 20 of a latch bolt 21 engages the shoulder and is slidable in the bore 17 against the tension of a coiled spring 22 confined by a plug 23. The bolt extends through the bore 19 and its end is engaged in a seat 24 in the end of the opposite hook, thus closing the gap between the hooks.

In Fig. 1 I have shown the link 10 connected with the combination clamps A of two sections B and C of a pumping rod. The section B is connected with the pumping power (not shown) while the section C is connected with the pump jack (not shown) at the well. The pumping rod is under more or less of a heavy load, according to the depth of the well and the length of the sucker rod.

When it is desired to stop pumping a well it is customary to place a block of wood (not shown) between the adjacent clamp A and the knock-off post D. The block is placed upon the back stroke of the rod while the clamp is moving away from the post and

thus, when the section B is moved forwardly on the return stroke the section C and its clamp A, remain stationary. This provides sufficient slack to free the clamp A of the 5 section B in the link, and to take the load off of the link. However the section B will slide its clamp A forwardly in the link and in the C-link now in common use, the 10 operation must be dexterous to prevent injury to his hand.

By provision of the hand grip 13 and the 15 opening 12 the operator is given a safe place on the link in which to place his hand and he may remove or disconnect the link with safety. In the form shown in Figs. 3 and 20 4 the bolt 21 must be displaced before the link can be disconnected, but this can be safely done with the other hand. The combination of the hand grip and the reinforcing web 11 and fins 14 is a very useful one and makes for a more efficient and satisfying link. The fins take the greatest strain and prevent spreading or distortion of the link.

Various changes in the size and shape of 25 the different parts as well as modifications and alterations may be made within the scope of the appended claims.

What I claim, is:

1. A C link for pumping rods comprising 30 a link body having a hook-shape formation at each end thereof and provided with a laterally projecting web having an opening therein and a hand grip contiguous to the opening.

2. A C link for pumping rods including 35 a body, a reinforcing web along one side of the body, a hand grip integral with the web, and radial reinforcing fins at the ends of the body.

3. A C link for pumping rods including a 40 body, a reinforcing web along one side of the body having an elongated opening, a hand grip contiguous to the opening of the web, and radial reinforcing fins at ends of 45 the body merged from the web.

In testimony whereof I affix my signature.
OSCAR C. STAPLES.
